UNITED STATES PATENT OFFICE.

RUDOLPH HOFFMAN, OF KANKAKEE, ILLINOIS, ASSIGNOR TO SEARS, ROEBUCK AND COMPANY, OF CHICAGO, ILLINOIS, A CORPORATION OF NEW YORK.

COOK-STOVE.

1,318,560.

Specification of Letters Patent. Patented Oct. 14, 1919.

Application filed April 20, 1918. Serial No. 229,717.

To all whom it may concern:

Be it known that I, RUDOLPH HOFFMAN, a citizen of the United States, residing at Kankakee, in the county of Kankakee and 5 State of Illinois, have invented certain new and useful Improvements in Cook-Stoves, of which the following is a specification.

This invention relates to improvements in water heaters of the type wherein the 10 utensil-supporting grid of a fluid-fuel cook stove is chambered to contain water, and wherein the grid is connected to a water reservoir built into the stove.

In the accompanying drawings Figure 1 15 is a fragmental top plan view of a stove embodying the features of my invention. Fig. 2 is a fragmental front elevation. Fig. 3 is a section on line 3-3 of Fig. 4. Fig. 4 is a section on line 4-4 of Fig. 2.

20 In the drawings, A denotes a frame of any suitable character. 1 is an oil feed pipe, 2 a burner of the wickless perforated-combustion-tube type, and 3 a drum surrounding the combustion tubes (not shown).

25 Any other suitable form of burner may, however, be employed. 4 is the top plate of the stove. In said top plate is an opening 5 directly above the burner to receive a grid 6. Said grid comprises a tubular an-

30 nulus 7 and a plurality of tubular radial arms 8 communicating with each other and with the annulus. Other arrangements of tubular elements communicating with various portions of the annulus may, however, 35 be used without departing from the invention.

The annulus 7 is connected to a reservoir 9 by means of pipes 10 and 11. The pipe 10 which supplies water to the grid connects 40 with the lower side of the annulus 7 at a point 12 between two of the arms 8. The pipe 11 is connected to the side of the annulus at 13 in a plane above the intake 12 and at a point between two arms 8. The 45 inlet 12 and the outlet 13 are approximately 90° apart. As shown in Fig. 2, the pipe 10 connects with the reservoir at a point below the plane in which the pipe 11 communicates with the reservoir.

50 The reservoir is divided by a partition 14 into two compartments 15 and 16. Communication between the compartments is established through a relatively small opening 17 formed in the partition 14 and pref-

erably located close to the bottom of the 55 reservoir. 18 is a cover for the reservoir, said cover being hinged at 19. The reservoir may be mounted upon and secured to the stove frame in any suitable way.

In operation, when a cooking utensil, 60 flat-iron or other article is placed upon the grid 6, the heat generated by the burner is transmitted not only to such article but also to the water in the grid.

The warmed water flows out through the 65 pipe 11 and is replaced by relatively cool water flowing into the grid through the pipe 10. Inasmuch as the inlet 12 and the outlet 13 are a substantial distance apart, and one of the arms 8 connects with the annulus 7 at a point between the inlet and the outlet, water does not short-circuit from the inlet to the outlet to any material extent.

By reason of the partition 14, hot water 75 accumulates in the compartment 16, the cooler water in the lower portion of said hot water compartment flowing through the opening 17 into the compartment 15 and thence through the pipe 10 to the grid. 80 Hot water thus becomes available for use much more quickly than if circulation in the reservoir were unrestricted.

Water may be removed from the reservoir by means of a dipper or the like when 85 ever desired.

20 are screw plugs for closing openings necessarily formed in the operation of casting the grid.

The reservoir is rigidly secured to the 90 stove frame in any suitable way, and the grid is held in place in any desired manner as by reason of its connection to the pipes 10 and 11.

Various changes may be made in the construction herein shown without departing 95 from the scope of the invention as set forth in the appended claim.

I claim as my invention:

A cook stove having, in combination, a 100 burner, a hollow grid above the burner having a water inlet and a water outlet, a reservoir, the lower portion of which is disposed in the horizontal plane of the grid, a vertical partition in the reservoir forming hot 105 and cold water compartments, and a pair of pipes connecting said compartments with said inlet and outlet of the grid, respec-

tively, so as to permit the water in the cold water compartment to flow to the grid to be heated by the burner and when heated to flow from the grid to the hot water compartment, there being an opening in the 5 partition near the lower portion thereof to permit the cooler water in the hot water compartment to flow by the action of gravity into the cold water compartment and thence to the grid for reheating. In testimony whereof, I have hereunto set my hand. 10

RUDOLPH HOFFMAN.
